UNITED STATES PATENT OFFICE.

JAMES W. ADAMS, OF NEWARK, NEW JERSEY, ASSIGNOR TO THOMAS W. ADAMS & CO., OF NEW YORK, N. Y.

DESIGN FOR A COMB.

SPECIFICATION forming part of Design No. 24,942, dated December 3, 1895.

Application filed October 28, 1895. Serial No. 567,198. Term of patent 7 years.

To all whom it may concern.

Be it known that I, JAMES W. ADAMS, of Newark, in the county of Essex and State of New Jersey, have invented and produced a new and original Design for Combs, of which the following is a specification, reference being had to the accompanying drawing, forming a part thereof.

The leading feature of my design consists in a comb having a tri-armed head and prongs extending from the head.

In the accompanying drawing the comb is represented in elevation, the three arms of the head being denoted by a a' a^2 and the prongs, which extend from the head, by b b' .

The arms are represented as heart-shaped, with the prongs merging into a common body portion A , from which the prongs b b' extend, and the ends of the arms are surmounted by crowns of filigree-work represented by c c' c^2 . 20

What I claim is—

The design for a comb, as herein shown and described.

JAMES W. ADAMS.
